BUBBLE GUN

Mahlon E. Hirsch, Fairview, Pa., assignor to Louis Marx & Company, Inc., New York, N.Y., a corporation of New York

Application April 27, 1959, Serial No. 55,678

Term of patent 14 years

(Cl. D34—15)

Fig. 1 is a top plan view of a bubble gun showing my new design;

Fig. 2 is an end view looking toward the stock;

Fig. 3 is an end view looking toward the muzzle;

Fig. 4 is an elevation showing one side of the gun; and

Fig. 5 is an elevation showing the opposite side of the gun.

I claim:

The ornamental design for a bubble gun, substantially as shown.
